ADJUSTABLE FORM LOCKING CHASE
STRUCTURE

Henry J. Hilland, Chicago, Ill.

Application December 12, 1946, Serial No. 715,764

11 Claims. (Cl. 101—393)

1

This invention relates to a form locking-up device, and its principal object is to provide improved "lock-up" mechanism for locking up printing forms and at the same time to dispense with printer's quoins, printer's furniture or other lock-up material, in the locking up of forms within or without a printer's chase, press, galley or the like.

Another object is to provide improved locking-up mechanism that can be adjusted to fit any printer's chase, press, galley or the like without in any way altering the manufactured form of any of these devices.

Another object is to provide improved locking-up mechanism that enables forms to be locked up without any strain or stress upon the chase or press; the strain going against the form.

Another object is to lock the lock-up means in the adjusted position thereof, whereby vibration or jars cannot loosen the locking bars from their hold against the form or type, and can be locked up at any predetermined position in the chase or press.

With these and other objects and advantages in view, this invention consists in the several novel features hereinafter fully set forth, and more particularly defined in the appended claims.

Fig. 1 is a plan of a chase with a form locked up therein by a form locking up device embodying one form of the invention;

Fig. 2 is a vertical longitudinal section taken on the line 2—2 of Fig. 1;

Fig. 3 is an enlarged vertical cross-section through one of the lock-up devices taken on the line 3—3 of Fig. 1;

Fig. 4 is a fragmental perspective view of one of the lock-up bars seen in Figs. 1 and 2;

Fig. 5 is a detail vertical longitudinal section of one of the lock-up devices taken on the line 5—5 of Fig. 1;

Fig. 6 is a view similar to Fig. 5, but showing the bar locking means in unlocked position;

Fig. 7 is a plan of fragments of two intersecting lock bars, and one of the adjustable lock-up means, showing one lock bar partly broken out to illustrate parts located below the same;

Fig. 8 is a fragmental plan illustrating a modified form of the invention;

Fig. 9 is a vertical longitudinal section taken on the line 9—3 of Fig. 8;

Fig. 10 is a fragmental plan of a second modified form of the invention;

Fig. 11 is a detail vertical section taken on the line 11—11 of Fig. 10; and

2

Fig. 12 is a side elevation of a key used in locking-up forms.

Referring to said drawings, and first to Figs. 1 to 7 inclusive, the reference character 10 designates a printer's chase of conventional form, in which other forms, set type, a cut or the like 11 is to be locked up in the chase.

A pair of parallel lock-bars 12, 12 extend lengthwise of the chase in the open space thereof, and a pair of parallel lock-bars 13 extend transversely in the chase in the open space thereof, and at right angles to the lock-bars 12. If desired, the two lock-bars 12 may comprise upper and lower bars 14, 15 secured together at their ends by spacers 16 and screws 17, or they may be spot welded or otherwise secured together by the spacers. The bars 13 extend through the spaces between the bars 14, 15, and sufficient clearance is left between the bars 14, 15 and the lock-bars 12 to permit sliding movement between the two pairs of lock-bars. Each lock-bar may have a threaded stud 18 secured in each end thereof, and threadedly mounted on each stud is a disc 19, which may be turned up against the inner sides of the chase to firmly lock the form locking-up device to the chase. Holes 20 may be formed in the edges of each disc to receive a pin or other tool for turning the disc.

Slidably connected with the lock-bars at their intersections with each other are lock-up means indicated generally by the reference character 21 for tightening the lock-bars against the form or job, and locking them in such position. In accordance with the form of the invention illustrated in Figs. 1 to 7, each lock-up means comprises a slide 22, having a hollow block 23 rising from the base 22a of the slide. In the hollow of the block are two pinions 24, 25, one superimposed upon the other with the teeth of the pinion 24 protruding through a slot in the block 23, and meshing with rack-teeth 26 formed on the upper bar 14 of the lock-bar 12. The lower pinion 25 meshes with a pinion 25a journaled on a pin 25b which rises from the base 22a of the slide and said pinion 25a meshes with rack-teeth 27 of the lock-bar 13. The pinion 24 is formed with a stub shaft 32, which is journaled in a bearing aperture 33 formed in the upper wall of the block 23, and the pinion 25 is likewise formed with a stub shaft 35, which is journaled in a bearing aperture 36 formed in a plug 31, which is rigidly held in an opening formed in the lower wall of the block 23, as by a press fit. In the stub shafts 32, 35 are formed sockets 40, 41, into which a wrench key or other tool T (see Fig. 12) may be inserted

for the purpose of rotating the pinions. The socket 40 is of greater diameter than the socket 41, whereby one tool may engage in the socket 40 and rotate the pinion 24 without rotating the pinion, and a tool of lesser diameter may enter the socket 41 to rotate the pinion 25 without rotating the pinion 24. Rotation of the pinion 24 in one direction moves the slide 22 along the lock-bar 12, and rotation of the pinion 25 moves the slide along the lock-bar 13.

Each lock-bar is preferably provided with a longitudinal extending groove 43, in which travels a lug 45 which projects from the slide. The groove end lug connections provide means for guiding the slide to move along both lock bars.

The slide is further provided with two sets of locking means designated generally by the reference character 46, to lock the slide to each of the intersecting lock-bars associated therewith, whereby to prevent vibration from loosening the lock-bars from the form. As shown, each locking means comprises a worm 46¹, rotatably mounted between ears 42, 47, which extend up from the base of the slide. A headed pin or screw 49 extends through the worm and through slots 50 in the ears 42, 47. The worm is moved toward and away from the teeth of the racks by a yoke-shaped finger piece 51, having arms 52 pivotally mounted on the pin 49, and having curved slots 53 non-concentric with respect to the pin 54. The pin 54 is secured in the ears 42, 47 of the slide and extends through the slots 53 in the arms 52, and causes movement of the arms and therewith the pin 49 and worm 46¹ toward and away from the lock-bar rack. When the finger piece is swung downwards to the position seen in Fig. 5, it moves the worm 46¹ toward and into mesh with the teeth of the associated rack. The teeth of the worm are helically disposed thereon to enable them to be meshed with the teeth of the rack in any adjusted position of the slide, and the teeth are notched at several places around their circumference to facilitate turning the worm into mesh with the teeth of the rack. If desired, the threaded pin 49 may be threaded in one of the arms of the finger piece so that by turning up the threaded pin tightly, the finger piece will be clamped against movement.

In operation the lock-bars are moved up against the form, and the pinions rotated to bring the lock-bars tightly against the form, and the finger pieces are then depressed, thereby meshing the worms with the rack teeth.

In the modified form of the invention, illustrated in Figs. 8 and 9, the form 11^a is surrounded by type high foundry bars 60. In this form of the invention the lock-bars 12¹ and 13¹ are of the same thickness, so that one may lie above and across the other, their ends being formed with heads 61, in which are secured threaded stems 18, upon which are threaded discs 19, as in the preferred form.

The lock-up means 21 is constructed substantially in the same manner as the corresponding lock-up means of the preferred form of the invention, and the form locking-up device is secured in a chase 10, as in the preferred form. This modified form of the invention is shown as applied to a foundry form.

In the forms of the invention hereinbefore described, double lock-up devices are provided—that is to say, the double lock-up means operates on two lock-up bars.

In the form of the invention illustrated in Figs.

10 and 11, a single lock-up device 21¹ is illustrated in connection with a short lock-up bar 12², which bears against the lock-up bar 13¹. In this form of lock-up device only one pinion 24¹ is employed, which meshes with the rack teeth of the lock-bar 12². This form of the invention is illustrated in connection with a foundry form, in which the form 11^a is locked in place in the chase. 60¹ designates type high foundry bars that surround the form.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a form locking-up device, a lock-bar adapted to lie across the space within a printer's chase, said lock-bar being adapted to engage one side of a form, and having rack teeth along one edge, a second lock-bar extending at right angles to the first mentioned lock-bar and in the space within the chase, and having rack teeth along one edge, a lock-up device slidably guided upon the last mentioned lock-bar, and having a hollow block formed thereon, arranged to engage the first mentioned lock-bar, and a pinion journaled in the block and meshing with the rack teeth of the second mentioned lock-bar, said pinion having a socket adapted to receive a tool for rotating the pinion, and bar locking means carried by the lock-up device and adapted to mesh with the teeth of the lock-bar with which the pinion meshes to prevent relative motion between the lock-up device and said lock-bar.
2. In a form locking-up device, two pairs of intersecting lock-bars adapted to be placed around the sides of a form, each lock-bar having rack teeth along one edge, a lock-up device having means cooperating with means on the lock-bars for guiding the lock-up device to move along said lock-bars, and pinions rotatably mounted in the lock-up device and meshing with the rack teeth of the lock-bars, certain of said pinions each having a socket for the reception of a tool.
3. In a form locking-up device, longitudinally and transversely extending intersecting lock-bars, each having rack teeth along one edge, slides guidably mounted on said lock-bars at their intersections, pinions rotatably mounted on said slides and meshing with said rack teeth, and two bar locking means carried by the slides and adapted to mesh with the rack teeth to prevent relative movement between the slides and lock-bars.
4. In a form locking-up device, longitudinally and transversely extending intersecting lock-bars, each having rack teeth along one edge, slides slidably guided on said lock-bars at their intersections, pinions rotatably mounted on said slides and meshing with said rack teeth, and toothed bar locking means rotatably mounted on the slides and adapted to mesh with the rack teeth to prevent movement between the slides and locking bars.
5. In a form locking-up device, longitudinally and transversely extending intersecting lock-bars, each having rack teeth along one edge, slides slidably guided on said lock-bars at their intersections, pinions rotatably mounted on said

slides and meshing with said rack teeth, upstanding ears carried by said slides, toothed locking worms rotatably mounted on said ears and adapted to mesh with the rack teeth of the bars to prevent relative movement of the slides and lock-bars.

6. In a form locking-up device, longitudinally and transversely extending intersecting lock-bars, each having rack teeth along one edge, slides slidably guided on said lock-bars at their intersections, pinions rotatably mounted on said slides and meshing with said rack teeth, upstanding ears carried by said slides, two toothed locking worms rotatably mounted on said ears and adapted to mesh with the rack teeth of the bars to prevent relative movement of the slides and lock-bars, finger pieces, one pivotally connected to each worm and having eccentric connections with the ears whereby to mesh the teeth of the worms with the rack teeth.

7. In a form locking-up device, longitudinally and transversely extending intersecting lock-bars, certain of the lock-bars having slots therein, through which other lock-bars extend, each lock-bar having rack teeth along one edge, slides slidably guided on said lock-bars at their intersections, pinions carried by said slides and meshing with the rack teeth of the lock-bars, and toothed locking means carried by the slides and adapted to mesh with the rack teeth to prevent relative movement between the slides and lock-bars.

8. In a form locking-up device, longitudinally and transversely extending intersecting lock-bars, certain of said lock-bars extending above others, each lock-bar having rack teeth along one edge, slides slidably guided on said lock-bars at their intersections, pinions rotatably mounted on said slides and meshing with the rack teeth of the lock-bars, and toothed locking means carried by the slides and adapted to mesh with the rack teeth to prevent relative movement between the slides and lock-bars.

9. In a form locking-up device, a lock-bar adapted to lie across the space within a printer's chase, said lock-bar being adapted to engage one side of a form, and having rack teeth along one edge, the second lock-bar extending at right angles to the first mentioned lock-bar and in the space within the chase and having rack teeth

along one edge, a lock-up device slidably guided upon said bars, and having a hollow block formed thereon, and a pinion journaled in the block and meshing with the rack teeth of one of the lock-bars, said pinion having a socket adapted to receive a tool for rotating the pinion, bar locking means carried by the lock-up device and adapted to mesh with the teeth of the lock-bar with which the pinion meshes to prevent relative motion between the lock-up device and the associated lock-bar, and locking discs on the ends of the lock-bars adjustable with respect to the lock-bars and adapted to be impinged against the inner sides of a chase.

15. In a form locking-up device, a lock-bar having rack teeth thereon, a slide slidably connected with said lock-bar and formed with an upstanding hollow block, a pinion rotatably mounted in said block and meshing with said rack teeth, said pinion having a non-circular socket therein for the reception of a key, a toothed bar locking element carried by said slide, and a finger piece for projecting the teeth of the locking element into mesh with the rack teeth, whereby to prevent relative movement between the slide and lock-bar.

20. In a form locking-up device, a longitudinally extending lock-bar and a transversely extending lock-bar intersecting the same, each of said lock-bars having rack teeth along one edge, a slide slidably guided to move along both lock-bars, two pinions, one superimposed upon the other and rotatably mounted on said slide, one of said pinions meshing with the rack teeth of one of the bars, a third pinion rotatably mounted upon the slide and meshing respectively with the other pinion and with the rack teeth of the other lock-bar, and bar locking means carried by said slide and adapted to lock the slide to the bars whereby to prevent relative movement between the slide and bars.
